UNITED STATES PATENT OFFICE.

JAMES H. REICHART, OF MUNCIE, INDIANA, ASSIGNOR TO THE STEROLECTRIC COMPANY, OF MUNCIE, INDIANA, A CORPORATION OF INDIANA.

THERMOSTATIC ELECTRIC SWITCH.

1,415,050.

Specification of Letters Patent.

Patented May 9, 1922.

Application filed October 7, 1920. Serial No. 415,379.

To all whom it may concern:

Be it known that I, JAMES H. REICHART, citizen of the United States, residing at Muncie, in the county of Delaware and State 5 of Indiana, have invented a certain new and useful Improvement in Thermostatic Electric Switches, of which the following is a full, clear, concise, and exact description.

My invention relates to switches, some of 10 the features of the invention including a thermostatic element as one of the switch contacts, while other features of the invention are not necessarily limited to the employment of such a contact.

15 It is one of the objects of my invention to provide an improved means for adjusting the gap between the contacts to vary the extent of movement of the traveling contact to bring it into engagement with the contact 20 complemental thereto. In carrying out this feature of my invention one of the contacts is mounted to turn and has portions engageable with the other contact, these portions being located at different distances from the 25 axis of movement of the contact having these portions. In the preferred embodiment of this feature of my invention the said contacting portions upon the rotatable contact are provided upon the periphery of this contact, this periphery being eccentric with respect to the axis of this contact.

In accordance with a second feature of 30 my invention the movable contact is in the form of a thermostatic element formed of two strips of metal having different coefficients of expansion, there being a stop for holding the thermostatic contact out of engagement with the other contact when the temperature is below a predetermined point 35 and permitting the thermostatic contact to engage the other upon sufficient increase in temperature while the stop is functioning and to move away from the supporting influence of said stop upon further increase 40 in temperature and while said contacts are still engaged. In the preferred form of this second feature of my invention the thermostatic contact is mounted upon a weighted arm which is normally supported by the 45 stop to maintain the thermostatic contact out of engagement with the other and permitting the thermostatic contact to engage the other upon a predetermined increase in temperature and while the stop still supports the arm, the thermostatic contact, 50

upon further increase in temperature, serving to move the arm out of the supporting influence of said stop while the contacts are still engaged.

The switch of my invention is of particular service in controlling the flow of current to a heating element (which may be employed, for example, in an electric cooking range or an electric fireless cooker), the thermostat being disposed within the influence of the electrically produced heat to close the contacts of the switch when a predetermined heat has been reached, there being in the circuit controlled by the switch an electro-magnetic circuit opening switch 60 which is then operated to open the circuit carrying the heating current. By adjusting the initial or normal distance between the contacts the amount of heat required to close the thermostatic switch may be varied 65 to suit the service to be performed by the heating unit. However, after the heating current has been turned off the thermostatic switch continues to be influenced and is further bent by the electrically produced heat. The pivoted weighted arm permits of this further bending or deflection of the thermostatic contact that continues to engage its complement without any more pressure than that initially effected by the 70 weight of the arm.

The accompanying drawing illustrates the preferred form of the invention having the foregoing characteristics. In the drawing Fig. 1 is a view in elevation, partially in 75 section, of the preferred form of switch in idle condition; Fig. 2 is a plan view, partially in section; Fig. 3 is an end view; and Fig. 4 illustrates parts of the switch when in action.

Like parts are indicated by similar characters of reference throughout the different figures.

The contact 1 is in the form of a plate with a contacting periphery eccentric to 100 the rotatable shaft 2 upon which this plate is mounted. This shaft is journaled in a metal bracket 3 supported upon the metal frame 4. Binding nuts 5 are insulated from the frame but are electrically connected with the bracket and through this bracket and the shaft 2 with the contact 1. The distance between the contact 1 and its complement 5' is adjusted by turning the shaft 2 with obvious results.

The contact 5' is preferably thermostatic, being formed of metal strips 6 and 7 that are preferably respectively brass and steel, the brass strip having a greater co-efficient of expansion than the steel strip so that when the thermostat is subject to sufficient heat it will bend into arcuate form. The bimetal contact is preferably mounted upon a comparatively heavy arm of steel which is pivoted at its outer end to exert pressure upon the thermostatic contact toward its complement. Until the heat has reached a predetermined value, the stop 9 will hold the thermostatic contact away from its complement but when the temperature has been sufficiently increased the thermostatic contact will be bowed sufficiently to rise from the stop, whereupon the weighted arm 9 will exert the contacting pressure. Any further bowing of the thermostatic contact will not increase the contacting pressure, nor will the contacting pressure be decreased when the thermostatic element straightens until in the act of separation of the contacts.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

1. A thermostatic switch having two engageable contacts one of which is a thermostatic contact to make it movable toward and from the other and formed of two strips of metal having different co-efficients of expansion; a movable weighted arm carrying the thermostatic contact; and a stop for supporting the arm and serving to hold the thermostatic contact out of engagement with the other contact when the temperature is

below a predetermined point and permitting the thermostatic contact to engage the other upon sufficient increase in temperature while the stop is functioning and to move the arm from the supporting influence of said stop upon further increase in temperature and while said contacts are still engaged.

2. A thermostatic switch having two engageable contacts one of which is a thermostatic contact to make it movable toward and from the other and formed of two strips of metal having different co-efficients of expansion; and a stop for holding the thermostatic contact out of engagement with the other contact when the temperature is below a predetermined point and permitting the thermostatic contact to engage the other upon sufficient increase in temperature while the stop is functioning and to move away from the supporting influence of said stop upon further increase in temperature and while said contacts are still engaged.

3. A thermostatic switch having two engageable contacts one of which is a thermostatic contact to make it movable toward and from the other; a movable weighted arm carrying the thermostatic contact; and a stop for supporting the arm and serving to hold the thermostatic contact out of engagement with the other contact when the temperature is below a predetermined point and permitting the thermostatic contact to engage the other upon sufficient increase in temperature while the stop is functioning and to move the arm from the supporting influence of said stop upon further increase in temperature and while said contacts are still engaged.

In witness whereof, I hereunto subscribe my name this twenty-first day of August, A. D. 1920.

JAMES H. REICHART.
